his Attorney's

UNITED STATES PATENT OFFICE.

EDWARD H. BINNS, OF PITTSBURGH, PENNSYLVANIA.

DESIGN FOR A COMBINATION DESK ARTICLE.

50,901.

Specification for Design.

Patented June 12, 1917.

Application filed February 8, 1917. Serial No. 147,503. Term of patent 14 years.

To all whom it may concern:

Be it known that I, EDWARD H. BINNS, a citizen of the United States, residing at Pittsburgh, in the county of Allegheny and State of Pennsylvania, have invented a new, original, and ornamental Design for a Combination Desk Article, of which the following is a specification.

Referring to the accompanying drawing, forming a part of this specification:

The figure is a perspective view of a com-

bination desk article, showing my new design.

I claim:

The ornamental design for a combination desk article, as shown.

In testimony whereof I affix my signature in the presence of two witnesses.

EDWARD H. BINNS.

Witnesses:

R. CLEMENT WEBER,
JENNIE JONES.
